UNITED STATES PATENT OFFICE.

THOMAS J. FITZ HARRIS, OF NEW ROCHELLE, NEW YORK, ASSIGNOR TO FRANKLIN SIMON & CO. INC., OF NEW YORK, N. Y., A CORPORATION OF NEW YORK.

DESIGN FOR A SHOE.

Application filed January 7, 1928. Serial No. 24,767. Term of patent 3½ years.

To all whom it may concern:

Be it known that I, THOMAS J. FITZ HARRIS, a citizen of the United States, and a resident of New Rochelle, in the county of Westchester and State of New York, have invented a new, original, and ornamental Design for a Shoe, of which the following is a specification.

Reference is had to the accompanying drawing, forming part thereof, wherein:

I claim:

The ornamental design for a shoe, substantially as shown.

Signed at New York in the county of New York and State of New York this 5th day of January, A. D. 1928.

THOMAS J. FITZ HARRIS.
